UNITED STATES PATENT OFFICE.

JARED B. FRENCH, OF RUTHERFORD, NEW JERSEY.

ROOFING.

Application filed March 24, 1927. Serial No. 177,980.

This invention relates to roofing and more particularly to the type of roofing which is fabricated from flexible asphalt-base material, and which is adapted to be laid in overlapping courses with the adjacent unit of each course widely spaced from each other. In order to afford sufficient protection for the roof, it is, however, essential to lap the adjacent elements in such manner that rain will not drive up underneath the elements and reach the underlying roof boards. While roofing elements of the type herein referred to have been variously fashioned for the purpose indicated, it has been found necessary to employ an excessive amount of material for covering a certain amount of roof area in order to provide the requisite weatherproofing qualities. This is largely due to inaccuracies of laying, the probabilities of which must be reckoned with as a practical matter in devising effective roofs. Another objection to many of the forms heretofore devised arises from the wastage of material involved in cutting the elements from a sheet, such waste being troublesome to remove and adding materially to the cost of the elements.

Accordingly, one of the objects of the present invention is the provision of a shingle which is cut from a sheet of roofing material without waste, and yet is so proportioned that it may be laid with a minimum amount of overlap so as to thereby effect a saving in the material necessary to cover a given area.

As an additional feature of the present invention, the elements constructed as herein-after to be more fully described, include shoulder portions which may be utilized as a guiding means in properly spacing adjacent units in each course as well as to properly position the successive courses. In the absence of simple and effective guiding means for alining the elements and nailing, a certain amount of irregularity of overlapping of adjacent elements is almost inevitable even when the elements are laid by careful workmen. For this reason, it has heretofore been found necessary to lay wide-spaced elements with an excessive overlap since otherwise the roof would be subject to exposure of some of the nailheads and to places with no overlap at all due to practically unavoidable irregularities in spacing the elements. Hence in providing self-alining and self-spacing features according to this invention, it is intended to minimize in a practical way the

overlap required for safe protection and thus to economize on material.

With the foregoing, and other objects in view, embodiments of the invention are illustrated in the accompanying drawing, in which

Figure 1 represents a roofing element formed according to my invention.

Figures 2 and 3 represent slightly modified forms of roofing elements.

Figure 4 represents a sheet of roofing material of indeterminate length, illustrating the manner in which roofing elements according to the present invention may be cut therefrom without waste.

Figure 5 shows the appearance of the several elements of the kind shown in Figure 1 when assembled on the roof.

Referring in detail to the figures, the shingle of the present invention may be said to comprise a body portion 1, a head portion 2, and a bottom portion 3. This element is preferably composed of flexible roofing material such as is commonly employed in the industry, and comprises a felted base of rag, asbestos, or similar fibers, suitably impregnated with asphaltic or similar waterproofing material and coated with a layer of asphaltic material such as blown asphalt, and provided with a surfacing layer of crushed slate or other mineral matter partially embedded into the asphaltic coating.

Referring to Figure 1, it will be noted that the marginal side edges 6 and 8 of the head portion 2 and the bottom portion 3 respectively, are tapered downwardly and are defined by lines, which if extended, would form one continuous line, while the marginal side edges 7 of the body portion 1 are tapered upwardly at an angle substantially equal to the angle at which the edges 6 and 8 are downwardly tapered, so as to provide outwardly extending shoulders 9 at the upper end of the body portion 1, and similar shoulders 10 at the upper end of the bottom portion 3.

In view of this equality of the taper as above described, it will be perceived that the marginal edges 6 and 8 on each edge of the shingle are parallel to the marginal edge 7 on the opposite edge thereof. The extent to which the marginal edges 6 are offset from the upper extremity of the body portion is therefore substantially the same as the extent to which the marginal side edges 7 of the body portion are offset from the bottom portion 3.

so that the shoulders 9 and 10 are substantially equal,—the marginal side edges 7 of the body portion 1 joining the inward extremity of the shoulders 9 with the outward extremity of shoulders 10. The upper edge 11 of the element is substantially parallel with its lower edge 12, the marginal edges 6 forming with the upper edge 11 an acute angle which is the supplement of the obtuse angle formed by the marginal edge 8 with the bottom portion 12 of the element.

As previously mentioned, the shingle is preferably shaped with complementary sides so that it may be cut with others of the same shape from a sheet with no waste material except a negligible amount at the beginning and ending of a sheet. The manner in which such shingles are arranged in the sheet from which they are cut is illustrated in Figure 4, it being understood of course that the sheet may be any multiple of the width shown. Since the general contour of the shingle is a tapering one, alternate shingles in the sheet as shown in Figure 4 will be inverted. On account of the lighting effect due to the "grain" of the surface where the shingle is covered with crushed slate or the like which results in a slight but noticeable change of color tone according to the direction of the light falling upon it, it may be desirable to sort out alternate shingles thus cut from the strip in order to prevent confusion of shingles in mixed color tones.

The cutting of the shingles from the sheet may be accomplished in any preferred manner, for example, by passing the sheet between rolls, one of which is provided with a pair of knives, each shaped to form a zigzag cut across the sheet so as to sever successive shingles from the sheet; or the cutting may be done in two steps, the inclined lines of severance being cut in one step and the short connecting longitudinal cuts made by a separate step to complete the severance of the shingles from the sheet. Machines suitable for this purpose are well known in the art.

In order to effect economy in laying the units of the present invention, the head portions 2 and the bottom portions 3 of each unit are preferably of substantially the same depth,—the body portion having a substantially greater depth than the head portions and bottom portions. The provision of a greater depth in the body portion 1 than in the head and bottom portions, and the special manner in which this element is cut, enables these elements to be laid on the roof with a minimum amount of side-lap without sacrificing any of the protection which a roof of this character should provide.

Figure 5 shows the manner in which these units are assembled on the roof and by referring thereto it will be seen that they are adapted to be laid with the adjacent shingles of each course widely spaced from each other.

With shingles known in the prior art, it has not been possible to greatly increase the coverage attainable with a given type of shingle without sacrificing necessary protection. With the element embodied in the present invention, however, and by virtue of the peculiar configuration thereof, it is possible to effect a substantial saving in the amount of material required to cover a given roofing area without subjecting the resultant roof to defects arising from laying of the units with too small an amount of overlap. For example, it will be noted that when shingles are laid wide-spaced, the butt edge of any shingle is usually but little below the top edge of the shingle second below in the vertical row beside it. In other words, the edge 12 of a shingle in the course marked "D" (Figure 5) lies only a relatively short distance below the upper edge 11 of an adjacent shingle in course "A". Hence, a point of relative vulnerability appears due to the possibility of rain driving up diagonally under the edge 12 of a "D" course shingle and getting through just above the edge 11 of an adjacent "A" course shingle. Instead of being driven up by the wind, water may be backed up by ice formations. This danger is greatly reduced by applicant's shingles by reason of the sidewise projection of the head portion 2 of the shingle in the "B" course which is directly below the shingle in the "D" course. This protection is afforded by all three forms of shingle illustrated. Where the side edges are slanted as in Figures 1 and 2, this further increases the lateral distance which must be traveled by water along the path described above in order to penetrate the roof.

In Figure 5 the elements of the first course are indicated at A', A'', these elements being first laid with their horizontal edges parallel with the eaves of the roof and being superposed over a suitable starter course in the well known manner. In laying this first course, one of the shingles as herein shown may be employed as a pattern or guiding means to properly and accurately space the individual units of this first course. The ease with which successive courses are properly and accurately laid depends upon the accuracy with which the shingles of the first course are spaced and alined, inasmuch as the succeeding courses are guided in the laying thereof by the shoulders 10 of the units in the underlying course. Accordingly, in order to accurately lay the first course, the first shingle A' may be nailed down with its bottom edge 3 parallel with the eaves of the roof. Employing another shingle, by reversing the same end for end and holding the same in that position adjacent the shingle A', as shown in dotted lines at X in Figure 3, with the shoulder 10 of the guiding shingle abutting the lower right hand corner of the shingle A', the second shingle

A² is then placed with its marginal edge 8 adjacent the opposite edge of the guiding shingle, so that the lower left hand corner of the shingle A² abuts the shoulder 10 of the guiding shingle. The shingle A² is then nailed and the guiding shingle removed and similarly employed to properly space the succeeding shingles of the first course.

The second course indicated at B is then laid so that the corners formed at the extremities of the bottom edge 12 coincide with the corners formed at the juncture of the edges 8 and shoulders 10 of the units in the first course, the shoulders thereby serving as a means to properly gauge the distance to which successive courses overlie the course below. Since the segments 7 of the sides of each shingle are accordingly to this invention respectively parallel to the segments 6 and 8 of the opposite sides of the shingle, the length of the shoulders 9 and 10 will be determined by the amount of taper and the height of the body portion 1. As the length of the shoulder 10 largely determines the amount of minimum side lap of the shingles as laid in Figure 5, this side lap may thus be controlled to some extent by the choice of the taper of the shingle as a whole and the height of the body portion 1. As may be seen from Figure 5, the arrangement of the side-lapping portions of the shingles is such that a comparatively narrow side lap, e. g., three-quarters of an inch, is found to be ample for adequate protection against the weather since an overlap of this amount under the butt portion of the shingle means that considerably more overlap will be present under the head portion of the shingle where it is most needed. Thus the shape of the shingle affords a marked economy of material without diminishing the protective quality of the roof.

The units of the third and fourth courses C and D are laid in a manner similar to that described in laying the course B, and the procedure is continued until the entire roof is covered.

The head lap, or the distance which the bottom of the units in the third course overlap the units of the first course, will be substantially equal to the depth of the body portion 1 of the element in view of the fact that the head portion 2 and the bottom portion 3 are substantially equal in depth. Accordingly any desired amount of head lap may be provided by varying the relation of the depth of the body portion 1 to that of the body portions 2 and 3 while retaining equality in the depth of the portions 2 and 3. As an illustration, when using shingles which are 14 inches in length, the body portion thereof may be 6 inches deep, while the head portion 2 and the bottom portion 3 are each 4 inches deep, so that when the units are laid with a 4" exposure, the head lap

will be 6 inches. Thus when the roof is completely laid with the elements embodying the present invention, and in the manner herein illustrated, it will be found that substantially 190 square feet of material will 70 cover 100 square feet of roof area. The saving of material thereby effected accordingly amounts to substantially 23 square feet for each square of roofing area necessary to be covered. It is also to be noted that the completed roof presents hexagonal outlines 75 which are highly ornamental and pleasing to the eye of the observer.

In nailing the shingles in place, one nail is driven immediately above each of the shoulders 10, as shown at 16, so that each nail passes through the adjacent shingle of the underlying course at a point near the upper part of the body portion thereof, and also passes through the underlying shingle of the second 80 underlying course at a point adjacent the upper edge 12 thereof. Thus, while each shingle has only two nails driven therethrough, one along each edge, when the roof is completely laid, each shingle above the 85 starter course will have six nails passing therethrough,—three along each side thereof. As will be understood, this feature aids in providing a very secure roof, whereof the individual units are not subject to being 90 blown up and caused to curl by strong winds.

Figures 2 and 3 illustrate two slightly modified forms of shingles embodying my invention, both forms being capable of being cut without waste from a sheet, having head and butt portions of equal depth spaced by a body portion of greater depth, and guide shoulders for alining and nailing formed on the side edges. The form shown in Figure 2 is generally tapering or trapezoidal as in Figure 1, but the edges of the body portion are not parallel respectively with opposite side edges of the head and butt portions. The form shown in Figure 3 comprises side edges 100 perpendicular with respect to the top and bottom edges.

I claim:

1. A flexible roofing element adapted to be laid widely spaced with others in courses and comprising spaced, downwardly tapering portions and an intermediate upwardly tapering portion.
2. A roofing element having mutually complementary side edges with shoulders defining head, body and butt portions of the element, said head and butt portions tapering downwardly, and said body portion tapering upwardly and having its maximum and minimum widths substantially equal respectively to the minimum width of the head portion and the maximum width of the butt portion.
3. A roofing element having shoulders in the side edges thereof defining head, body and butt portions of the element, the relative average widths of said portions decreasing 120

in the order named, said head and butt portions being of substantially equal depth less than that of said body portion.

4. A roofing element having mutually complementary side edges with shoulders therein defining head, body and butt portions of the element, said body portion having an average width less than that of the head portion and more than that of the butt portion, said body portion also having a depth greater than that of either of the other two portions.

5. A roofing element having mutually complementary side edges with shoulders dividing the side edges into segments and defining head, body and butt portions of the element, the head and butt segments of each side edge being alined and at an angle with the corresponding body segment.

6. A flexible asphalt base roofing element adapted to be laid widely spaced with others in courses and comprising a body portion, a head portion, and a butt portion, the marginal side edges of the head portion converging downwardly and being substantially in alinement with the marginal side edges of the butt portion, and extending at an angle to the bottom edge of the element, the marginal side edges of the body portion being parallel with the opposite marginal side edges of the head and butt portions.

7. A flexible asphalt base roofing element adapted to be laid widely spaced with others in courses and comprising a body portion, a head portion, and a butt portion, the marginal side edges of the head portion being substantially in alinement with the marginal

side edges of the butt portion and extending at an angle to the bottom edge of the element, the marginal side edges of the body portion extending at an angle to the marginal edge 40 of the head portion on the same side of the element.

8. A roof composed of overlapping courses of flexible elements widely spaced in each course, each of said elements having a head 45 portion, a butt portion and an intermediate body portion, said three portions having different average widths, the body portion of each element in one course side-lapping the head portion of an adjacent element in an 50 underlying course to a greater extent than the intermediate portion of said element in said underlying course is side-lapped by the butt portion of said element in the first-named course. 55

9. A roof composed of overlapping courses of elements widely spaced in each course, each of said elements comprising spaced downwardly tapering portions separated by an intermediate upwardly tapering portion. 60

10. A roof composed of wide spaced elements laid in overlapping courses, each said element having side edges with shoulders defining three segments of each side edge, the elements being arranged with their lowermost 65 corners registering upon and with lower shoulders of the side edges of the elements in the course next below.

In testimony whereof I have affixed my signature.

JARED B. FRENCH.
